UNITED STATES PATENT OFFICE.

JOHN F. METTEN, OF PHILADELPHIA, PENNSYLVANIA, ASSIGNOR TO THE WILLIAM CRAMP & SONS SHIP & ENGINE BUILDING COMPANY, A CORPORATION OF PENNSYLVANIA.

TURBINE-ROTOR.

1,097,251.

Specification of Letters Patent. Patented May 19, 1914.

Application filed September 26, 1913. Serial No. 791,901.

To all whom it may concern:

Be it known that I, JOHN F. METTEN, a citizen of the United States, residing at Philadelphia, in the county of Philadelphia and State of Pennsylvania, have invented certain new and useful Improvements in Turbine-Rotors, of which the following is a full, clear, and exact specification.

10 This invention relates to the rotating members of elastic fluid turbines wherein the parts are subjected to variations of temperature which cause expansion and contraction.

15 Where the hubs of the bucket wheels of steam turbines are rigidly fixed against longitudinal movement on the shaft, difference in longitudinal expansion between the wheel hubs and the shaft is liable to cause whipping or bending of the shaft. This may throw the movable blades or buckets out of position and may even cause them to collide with the stationary blades. This may cause the blades to strip and the turbine to 25 be seriously damaged.

The main object of the present invention is to provide a means whereby the distortion and danger due to this unequal expansion may be avoided and this is accomplished by 30 permitting the wheel hubs to move along the shaft as they expand.

Other and ancillary objects of the invention will appear hereinafter.

The invention can be best described in 35 connection with the accompanying drawings, of which—

Figure 1 is a central longitudinal section partly broken away, of a turbine embodying the invention; and Fig. 2 is a detail on an 40 enlarged scale.

Referring to the drawings, within the casting 1 turns the rotor shaft 2. The interior of the turbine is divided into stages by means of the fixed partitions or diaphragms 3. Within these stages are mounted the bucket wheels as 4 which carry the circumferential rows of buckets or blading 5 between which extend the stationary intermediate blading 6. The hubs 10 of the bucket wheels are 45 slid upon the shaft 2 extending beneath the stationary diaphragms, and are held against rotation with relation to the shaft by means of the keys 11. The hubs of the bucket

wheels substantially cover the shaft and are held against longitudinal movement to the 55 left by means of a shoulder 12 which may be turned up on the shaft. The movement of hubs at the other end is limited by means of a nut 13 which is screw-threaded upon the shaft. Steam is admitted to the various 60 stages by means of nozzles as 7 in the diaphragms. In the turbine shown, provision is made for different speeds by varying the number of stages. Thus, in this structure, the highest speed is obtained when steam is 65 admitted to the chamber 8 and to the nozzles leading therefrom, the stages to the right being cut out, another speed being obtained by admitting steam to the chamber 9 and through the nozzles leading therefrom, this including two more stages and reducing the speed, while a still further reduced speed may be obtained by admitting steam initially to the extreme right-hand stage. 75

When steam is first admitted to any of the stages of the turbine, it comes in direct contact with the wheel hubs and on account of the leakage of the steam between the diaphragms and hubs this is the case throughout substantially the whole length of the hub. The result is that the hubs expand under the heat received from the steam and before this heat is transmitted to the shaft. This causes unequal expansion of the shaft 85 and hubs so that where suitable provision is not made for this expansion the shaft is liable to be whipped or bowed with danger of blading or other parts of the turbine coming into collision, with resultant damage to 90 the turbine. In this structure clearance is provided between the stationary abutment at the left and the nut at the right to permit the longitudinal movement of the wheel hubs under expansion, and this clearance is 95 distributed along the shaft, so that the relative movement of any given bucket wheel under expansion is insignificant so far as blade clearances are concerned. This is accomplished by dividing the hubs into groups 100 (two to a group in the structure shown) and placing abutments between the groups. These abutments are so spaced that they limit the longitudinal movements of the hubs within operative bounds. There is also 105 provided between each pair of adjacent abut-

ments a clearance sufficient to permit longitudinal movement of the hubs between them under expansion without unduly binding these hubs between the abutments. It will be seen that only such clearance will have to be provided between two adjacent abutments as will take care of the expansive movement of those hubs which are located between the abutments and so the necessary clearances for the wheel hubs will be distributed along the shaft and become insignificant at any given point.

In the structure shown the intermediate abutments 15 are removable so that the wheels can be readily assembled upon the shaft. These intermediate abutments are formed by making circumferential grooves in the shaft at the points where abutments are desired, and in each of these grooves a spring steel ring is sprung, this ring extending outside of the groove and forming the abutment. The ring may be secured in position by counter-boring an adjacent wheel hub so that it may overlap the ring. This structure is clearly shown in Fig. 2 wherein it appears that the wheel hub 10 is limited as to its longitudinal movement on the shaft 2 by the ring 15 fitting in a groove in the shaft and extending outwardly therefrom, the hub 10 being counter-bored and over-lapping the ring 15 which it holds in position, the expansion clearance being indicated at 18.

While the invention is illustrated in what is considered its best application, it may have other embodiments without departing from its spirit and is not therefore limited to the structure shown in the drawings.

Having thus described my invention, I declare that what I claim as new and desire to secure by Letters Patent, is:—

1. An elastic fluid turbine having a rotor comprising a shaft, a bucket wheel thereon, and means for limiting the longitudinal movement of the hub of said bucket wheel along said shaft but allowing for longitudinal heat expansion of said hub.

2. An elastic fluid turbine having a rotor comprising a shaft, a plurality of bucket wheels having their hubs mounted on said shaft and movable with relation thereto, and means for limiting the movement of said hubs upon said shaft but permitting their longitudinal movement with relation thereto under expansion by heat.

3. An elastic fluid turbine having a rotor comprising a shaft, a plurality of bucket wheels having their hubs mounted thereon and movable with relation thereto, and abutments on said shaft between which the hubs are located and which limit their longitudinal movement but permit such movement under heat expansion.

4. An elastic fluid turbine having a rotor comprising a shaft, a plurality of bucket

wheels having their hubs mounted thereon and movable with relation thereto, and abutments on said shaft between which the hubs are located and which limit their longitudinal movement but permit such movement under heat expansion, one of said abutments being adjustable.

5. An elastic fluid turbine having a rotor comprising a shaft, a plurality of bucket wheels having their hubs mounted thereon and movable with relation thereto, and abutments on said shaft between which the hubs are located and which limit their longitudinal movement but permit such movement under heat expansion, one of said abutments being a nut in screw-threaded engagement with said shaft.

6. An elastic fluid turbine having a casing, diaphragms dividing the interior of the casing into stages, nozzles for admitting elastic fluid to the stages and a rotor comprising a shaft, bucket wheels in the stages, said bucket wheels having their hubs mounted upon and movable with relation to said shaft, and means for limiting the longitudinal movement of the hubs upon said shaft but permitting their movement due to heat expansion.

7. An elastic fluid turbine having a rotor comprising a shaft, bucket wheels having their hubs mounted thereon and movable longitudinally with relation thereto, means for limiting the longitudinal movement of said wheels along said shaft but providing a clearance to permit of the movement of the wheel hubs under heat expansion, and means for distributing the clearance along the shaft.

8. An elastic fluid turbine having a rotor comprising a shaft, a plurality of bucket wheels having their hubs longitudinally movable upon said shaft, and a plurality of abutments along said shaft, a portion of the wheel hubs being included between two adjacent abutments.

9. An elastic fluid turbine having a rotor comprising a shaft, a plurality of bucket wheels having their hubs longitudinally movable thereon, abutments at the ends of the hubs for limiting longitudinal movement thereof but providing for their longitudinal movement under heat expansion, and means located between the said abutments for dividing the expansion clearance between a plurality of groups of bucket wheels.

10. In an elastic fluid turbine rotor, the combination with a shaft having a circumferential groove of a ring in said groove and a bucket wheel having its hub over-lapping said ring.

11. An elastic fluid turbine having a casing, diaphragms dividing the interior of the casing into stages, nozzles for admitting elastic fluid to the stages and a rotor com-

prising a shaft, bucket wheels in the stages, said bucket wheels having their hubs mounted upon and movable with relation to said shaft, and a plurality of abutments 5 along said shaft, a portion of the wheel hubs being included between two adjacent abutments.

In testimony whereof I affix my signature, in presence of two witnesses.

JOHN F. METTEN.
